UNITED STATES PATENT OFFICE.

ERNEST MOONEY, OF YORK, ENGLAND.

LUBRICATING DEVICE FOR RAILWAY VEHICLE AXLES.

Application filed December 28, 1923. Serial No. 683,125.

To all whom it may concern:

Be it known that I, ERNEST MOONEY, a subject of the King of Great Britain, residing at York, in the county of York, England, have invented certain new and useful Improvements in Lubricating Devices for Railway Vehicle Axles, of which the following is a specification.

This invention relates to that kind of railway axle lubricating device in which an absorbent pad connected to or formed integral with capillary feeders dipping into the oil in the axle-box is supported in contact with the journal by means of a spring frame or carrier constructed of flexible strip metal.

In employing this known lubricating device, considerable trouble has hitherto been experienced in effecting its removal from the axle-box even in the case where handle portions have been provided; and the object of this present invention is to provide the lubricating device with improved means by which its removal from the axle-box is rendered capable of being easily and speedily performed.

According to my invention, the spring frame of the lubricating device is provided on the forwardly projecting ends of its straight longitudinal side members with bearings in which is fulcrumed a double-ended lever having its inner arm pivoted to the forward end of the cradle of said spring frame and its outer arm left free to act as a manipulating handle; the arrangement being such that by rocking the double-ended lever the forward end of the absorbent pad is lowered clear of the enlarged end of the journal and by subsequently pulling the said double-ended lever the lubricating device as a whole is removed from the axle-box in an easy and speedy manner by reason of the pull so imparted being distributed between the top and bottom connections of the spring frame.

The double-ended lever, preferably of compound bell-crank formation, constitutes a permanent fitment to the spring frame of the lubricating device, and thus the said lever may also be utilized in facilitating the placing of the lubricating device into the operative position within the axle-box.

The invention will now be described with reference to the example of construction

shown in the accompanying drawings; 55 wherein:—

Fig. 1 is a longitudinal section of an axle-box showing the lubricating device in the operative position and having my improved fitment applied thereto, and Fig. 2 is a sectional plan view of Fig. 1 but with the axle and a portion of the absorbent pad omitted for the sake of clearness. Fig. 3 is a similar view to Fig. 1 but showing the lubricating device when being removed by the fitment, and Fig. 4 a sectional plan view of Fig. 3 but with the same portions omitted as in Fig. 2.

Referring to the drawings, 1 is the axle-box fitted with a hinged lid 2, while 3 is the axle and 4 the journal turning in bearings (not shown) in the axle-box 1. The known lubricating device consists of an absorbent pad 5 formed integral with capillary feeders 6 dipping into the oil in the axle-box 1 and being supported in contact with the journal 4 by means of a spring frame comprising a cradle 7, a transverse bearer strip 8 central to the cradle 7, a central longitudinal base member 9 attached to straight longitudinal side members 10 by transverse strips 11, and double elliptical longitudinal side members 12 attached to the longitudinal side members 10 and to the ends of the transverse bearer strip 8. 85

According to my invention, the forwardly projecting ends of the straight longitudinal side members 10 of the spring frame are formed with looped bearings 13 in which is fulcrumed a compound bell-crank lever 14 having its inner arm passed into pivotal engagement with lugs 15 fixed to the forward end of the cradle 7 of the said spring frame while its outer arm is left free to act as a manipulating handle. 95

Assuming the lubricating device to be in the operative position as shown at Figs. 1 and 2, the compound bell-crank lever 14 is rocked inwards on its fulcrum 13 until it assumes the position shown at Figs. 3 and 4, 100 whereby the forward end of the absorbent pad 5 is lowered clear of the enlarged end 4* of the journal 4 prior to the lubricating device as a whole being pulled forward by a forward pull imparted to the bell-crank 105 lever 14 as shown at Figs. 3 and 4, while a continued pull on said lever 14 ensures the easy and speedy removal of the lubricating

device as a whole from the axle-box 1 by reason of the pull so imparted being distributed between the top and bottom connections 15, 13 of the spring frame.

5 The compound bell-crank lever 14 constitutes a permanent fitment to the spring frame of the lubricating device, and thus the said lever 14 may also be utilized in facilitating the placing of the lubricating device into the operative position within the axle-box 1.

What I claim as my invention, and desire to secure by Letters Patent is:—

1. In a railway axle lubricating device 15 of the kind specified, the combination with a spring frame having straight longitudinal side members, an absorbent pad and capillary feeders, and a cradle therefor, of a double ended lever fulcrumed on the forwardly projecting ends of the straight longitudinal side members of the said spring frame and having its inner arm pivoted to the forward end of the said cradle, with its outer arm free to act as a manipulating handle.

2. In a railway lubricating device of the kind specified, the combination with a spring frame having straight longitudinal side members, an absorbent pad and capillary feeders, and a cradle therefor, of bear-

ings provided on the forwardly projecting ends of the said straight longitudinal side members of the spring frame, and a double ended lever fulcrumed in said bearings and having its inner arm pivotally attached to the forward end of the said cradle, with its outer arm free to act as a manipulating handle.

3. In a railway lubricating device of the kind specified, the combination with a spring frame having straight longitudinal side members, an absorbent pad and capillary feeders, and a cradle having lugs fixed on the forward end thereof, of looped bearings provided on the forward ends of the straight longitudinal side members of the said spring frame, and a double ended compound bell crank lever fulcrumed in the said looped bearings and having its inner arm passed into pivotal engagement with the said lugs on the forward end of the cradle, while its outer arm is free to act as a manipulating handle.

In witness whereof I have hereunto set my hand in the presence of two witnesses. 55

ERNEST MOONEY.
